(57) **CLAIM**

The ornamental design for a hair clipper housing, as shown and described.

DESCRIPTION

FIG. 1 is a perspective view of one embodiment of a hair clipper housing of the present invention;
FIG. 2 is a front view of the hair clipper housing of FIG. 1;
FIG. 3 is a right side view of the hair clipper housing of FIG. 1;
FIG. 4 is a left side view of the hair clipper housing of FIG. 1;
FIG. 5 is a rear view of the hair clipper housing of FIG. 1;
FIG. 6 is a top view of the hair clipper housing of FIG. 1;
FIG. 7 is a bottom view of the hair clipper housing of FIG. 1;
FIG. 8 is a perspective view of an alternate embodiment of the hair clipper housing of the present invention;
FIG. 9 is a front view of the hair clipper housing of FIG. 8;
FIG. 10 is a right side view of the hair clipper housing of FIG. 8;
FIG. 11 is a left side view of the hair clipper housing of FIG. 8;
FIG. 12 is a rear view of the hair clipper housing of FIG. 8;
FIG. 13 is a top view of the hair clipper housing of FIG. 8;
and,
FIG. 14 is a bottom view of the hair clipper housing of FIG. 8.
The broken line showing of the switch, contacts, housing interior, and interface is for illustration purposes only and forms no part of the claimed design.
